UNITED STATES PATENT OFFICE.

FRANK L. SESSIONS, OF COLUMBUS, OHIO, ASSIGNEE, BY MESNE ASSIGNMENTS, TO
THE JEFFREY MANUFACTURING COMPANY, A CORPORATION OF OHIO.

CIRCUIT-BREAKER FOR ELECTRIC CIRCUITS.

1,072,177.

Specification of Letters Patent.

Patented Sept. 2, 1913.

Application filed February 25, 1904. Serial No. 193,906.

To all whom it may concern:

Be it known that I, FRANK L. SESSIONS, a citizen of the United States, residing at Columbus, in the county of Franklin and State of Ohio, have invented certain new and useful Improvements in Circuit-Breakers for Electric Circuits, of which the following is a specification, reference being had therein to the accompanying drawings.

10. This invention relates to improvements in breakers for electric circuits.

It has for one of its objects to provide a circuit breaker in which the arcing occurring within the mechanism at the instant of the final break of the circuit therein is caused to take place between carbon contacts after the metallic contacts which are used have been separated, so as to avoid rapid deterioration of the metal contacts.

20. Another object of my invention is to provide means for timing the action of the circuit breaking mechanism under an over-load of current on the circuit, whereby the circuit will not be broken instantaneously, but 25 the said breaking will occur after a predetermined interval of continuance of the excess of current.

Figure 1 is a face view of a mechanism embodying my improvements, the face 30 plate of the casing being removed. Fig. 2 is a view partly in face elevation, with the plate removed, and partly in vertical section. Fig. 3 is a perspective showing the back of the casing, the magnet and some of 35 the upper contacts and terminals. Fig. 4 is a perspective showing the contact separating rod, the trigger, the tripping rod and hand lever for closing the circuit. Fig. 5 is a central vertical section of the apparatus. 40 Fig. 6 is a cross-section on line 6—6 of Fig. 5. Fig. 7 is a horizontal section on the line 7—7 of Fig. 5. Fig. 8 is a vertical section showing the checking or retarding device. Fig. 9 is a section of the spring and spring 45 actuated devices which hold the armature in normal position. Fig. 10 is an end view of the parts in Fig. 9.

In the drawings the apparatus is shown as provided with a casing having the back

wall 18, the top wall 18^a, the bottom 20, the 50 side walls 18^b, and the front detachable wall or cover 19, said bottom and side walls being preferably formed of non-magnetic material.

A represents a block of insulating material secured in position in the upper part of the casing. It serves to provide an insulating support for certain of the electric conductors within the casing.

22 is a binding post secured to the under- 60 side of the block A and adapted to receive the conductor through which the current enters the mechanism. 22^a indicates the base portion of the said binding-post to which the upper end or terminal 24 of the coil of 65 the blow-out magnet 24^a is secured. This coil, as a whole, is of the character of a spool, with suitable insulation between its convolutions.

12 indicates the metallic core of the mag- 70 net. It is preferably formed integral with the back wall 18 and like the said wall is composed of metal of high permeability. This core at its forward end is bifurcated, as shown at 12^a, 12^b.

75 12^a, 12^b are projections carried by the back piece 18, one arranged at either side of the casing and adapted to serve as poles for the magnet 24^a.

The current after passing through all the 80 convolutions of the coil, travels over the outgoing conductor section 25 to the stationary contact plate or brush 2. This brush or contact plate is secured to insulating plate A and is formed with the under-sloping or 85 tapered surface 2^a.

3^a is a binding-post secured to the insulating block A and adapted to receive the conductor through which the current passes from the mechanism. This binding-post has 90 extending inward from it the contact plate or brush 3 having its under edge sloping or tapered as indicated at 3^a.

4 is a carbon block secured to the under surface of the contact plate 3 and 6 is a 95 carbon block secured to the under surface of the contact plate 2.

1 indicates as an entirety a switch or mov-

able circuit closing member. This switch preferably consists of two sets of movable contact engaging elements or brushes. The upper one 30 is formed of a series of laminæ or plates of copper securely fastened together and held by an insulating holder 30^a which is secured to the upper end of the rod 29. The laminæ, or layers of copper increase in length downward so as to provide tapering or sloping ends for the brush which correspond to the tapered edges 2^a, 3^a of the contact plates 2, 3 with which they are adapted to engage. 1^a is a spring secured in the holder 30^a beneath the plates of copper therein and adapted to have its ends contact with the lower-most points of the contact plates 2, 3, respectively. One of the purposes of this spring is to exert a downward pressure on the rod 29 normally tending to force the brush 30 out of contact with the plates 2, 3. The second set of brushes operated by this switch comprises the carbon blocks 5 and 7 carried by a spring 8 secured in the insulating holder 30^a and adapted to engage with the carbon blocks 4 and 6 respectively. These carbon blocks 5 and 7 are preferably secured in holders 8^a which are pivotally mounted in bearing blocks 8^b secured to the opposite ends of the spring 8. 8^c are springs for holding the carbon holders yieldingly relative to the said spring 8.

26 is a flexible conductor held within the insulated holder 30^a and having its ends secured in the carbon holders 8^a and immediately adjacent to the carbon blocks 5 and 7. It is made of metal which is a good conductor of electricity and is adapted to insure good electrical connection between the carbon blocks.

40 The path of the current through the mechanism is as follows: It enters at the binding-post 22 and passes through the coil 24^a to the stationary contact 2. When the circuit is closed the current passes from the contact plate 2 through the brushes carried by the switch 1 to the contact plate 3 and thence through the binding post 3' to the main.

50 In order to break the circuit I provide mechanism for drawing the copper plates or laminæ of the brush 30 away from the contacts at 2 and 3 and subsequently separating the contacts 4, 5 and 6, 7. As stated these brushes are supported at the upper end of the carrier or rod 29. This rod is held and guided by a collar 29^a which is secured at 29^b to the core 12 of the magnet and extends down between the projections 12^a thereof.

55 28 is a spring surrounding the rod 29 and bearing upward against the collar 29^a and downward against the collar 29^c on the rod, the spring being compressed when the rod 65 is forced upward to cause the circuit within

the mechanism to be closed and, being under compression, is ready to quickly draw or thrust the rod downward when the latter is released from the locking device, to be described. The latter consists of a trigger-like device, indicated by 36, it having upright legs 36^a which are pivoted at 37 to a lug 37' on the bottom wall 20 of the casing. At its upper end this trigger-like device 36 has outwardly projecting arms 36^b which straddle the lower squared portion of the rod 29. The upper edges of these arms 36^b are curved, the curvature being concentric with the axis of the pivotal connection at 37.

70 35 are anti-friction rollers mounted on studs or pins carried by the rod 29. They are adapted to rest and roll upon the aforesaid curved edges of the arms 36^b.

75 38 is a spring secured at one end to an arm 38^a on the trigger device 36 and having its other end adapted to rest on the bottom wall 20 of the casing. This spring tends to normally hold the trigger device so that its arms 36^b maintain the rod 29 in that position where the brushes it carries close 80 the electrical circuit through the mechanism. When the trigger device 36 is swung rearward against the action of the spring 38 the rollers 35 on the rod 29 escape from the arms 36^b and the rod is quickly thrust 85 downward by the action of the spring 28.

90 The release of the rod 29 from the trigger is effected electromagnetically.

9 represents the armature of the magnet. It is supported by a bifurcated carrier pivoted at 10 and 11 to the casing.

100 At 9^a there is an aperture into which is loosely fitted a rod 14.

105 14^a is a pin in the rod 14 against which the armature can bear, and the aperture 9^a is of such shape that its own swinging movement and that of the rod 14 will be compensated for. The rod 14 has a loop 14^b, the ends of which are pivoted at 14^c to the aforesaid arms 36^b. If the lower end of the armature is forced inward it will through the rod 14, and the pin 14^a push the trigger device 36 back so as to release the rod 29. Such action of the armature occurs when the current passing through the above described path becomes too strong for then the magnet 24^a and its core 12 are energized to such an extent as to powerfully draw the armature inward.

110 At 15 there is a push button, which, through rod 15^a, enables the operator, whenever he desires, to break the circuit, for by pushing inward upon these parts he thrusts the rod 14 inward, which in turn pushes back the trigger device at 36 and allows the 115 rod 29 to drop. The push button 15 is not positively connected to the interior releasing mechanism, and merely contacts at its inner end with the outer end of the rod 14 as is shown in Fig. 7. As a result of this 120 130

construction, the rod 14 and the parts attached to it are free to move independently of the push button, and it is not therefore possible for the operator to hold the contacts in closed position by means of the push button if the current should exceed the amount for which the parts are adjusted. To enable the operator to restore the contact again, after the circuit has been automatically or otherwise opened, the hand lever at 31 is provided, the arm 32 of which, slotted at 33, engages with pins or with rollers at 34 on the contact rod 29. By swinging the lever in the proper direction the rod 29 will be pushed up until the rollers 35 get to points above and rest upon the lock arms 36^a. The under edges of these arms are so shaped as to be cam-like and when the rollers 35 strike said under edges they force the trigger-like device backward until they pass the points of the arms. By having the upper edges curved in the way described, that is concentric with the axis at 37, I attain important ends. The rollers or pins on the rod 29 cannot act to throw the trigger inward, they in fact, when pressing downward, forcing the trigger, if anything, outward toward its active position; but at the same time, when power is applied to the trigger it rolls with the least possible amount of friction under the rollers 35, and consequently there is a greater assurance that the desired action of circuit breaking shall occur than is incident to other mechanisms with which I am acquainted.

The armature 9 is normally held separate from the magnet core at 12 by means of a spring actuated plunger 13. This plunger and the compression spring 13' which controls it are arranged in a casing or cylinder 13^a having a longitudinal slot 13^b in which a lug 13^c on the piston 13 operates, the engagement of this lug with the inner end wall of the slot tends to limit the inward movement of the plunger.

13^a is a pin carried by the plunger 13. It extends through the cylinder and is adapted to engage with a downwardly projecting lip or ear 9^e on the armature 9. The cylinder 13^a has a projecting arm or lug 13^e which is secured at 13^f to the under-plate of one of the core arms 12^a and holds the cylinder in position.

It is frequently desirable, especially in locomotives for electric traction work, to employ very heavy currents for a few seconds in starting loads and for such purposes I have provided a time limit device which may be employed with the mechanism above described when desired, it being adapted to be adjusted so as to permit a heavy over-load to be carried by the circuit for a sufficient time to start the train. If this over-load continues for too great a period of time the circuit breaker will operate to break the

circuit, but if the over-load does not continue for the predetermined limit for which the retarding device is adjusted and the current through the circuit diminishes, the circuit breaker will not be opened.

In the drawings, 40 indicates as an entirety a retarding device of a style preferably for use in connection with the armature 9 above described. It comprises an oil cylinder, 41, communicating at its rear end through the duct 41', with an oil receiving chamber 42, and at its front end through a duct 41^a with an oil receiving chamber 43. 44 is a duct connecting the said oil receiving chambers 42 and 43.

45 indicates as an entirety a valve which is adapted to control the flow of oil through the duct 44.

46 is a piston or plunger adapted to operate in the cylinder 41 and 46' is the plunger rod which is pivotally connected at 46^a to a downwardly projecting lug 9^b arranged at one side of the armature 9.

The cylinder 40 and the oil chambers 42 and 43 may all be formed in a single casting, as shown in Fig. 8.

47 is a lug or projection on the cylinder 41 which is secured at 48 to the under side of one of the legs 12^a of the magnet core 12 and serves to support the cylinder and the parts connected with it in proper position relative to the armature 9.

44' is a conical recess formed at one end of the duct 44.

The control valve 45 comprises a screw 100 threaded stem or rod 49 which is hollow at its inner end as indicated at 49'.

50 is a hollow cap or valve head which is screwed on to the inner end of the valve stem 49. At its inner end 50' it is conically tapered to correspond with the recess 44' into which it is adapted to be adjusted.

50^a is a duct leading from the cap 50 and arranged to communicate directly with the duct 44. Within the interior of the said cap or valve head is arranged a spring controlled check valve comprising a ball 51 for which a seat is provided at the inner end of the valve stem 49. 52 is a spring normally pressing the said ball valve against its seat. 115

53 is a cap fitted to the outer end wall of the oil reservoir 43 and adapted to receive and guide the valve stem 49.

54 is a stuffing box for the cap 53.

49^a is a duct leading from the interior of the hollow end of the valve stem 49 and adapted to establish communication between the oil chamber 43 and the interior of the said valve stem.

55 is an index dial or wheel secured to 125 the outer end of the valve stem 49. Its periphery is notched as indicated at 55'.

55^a is a spring secured at its inner end to the under side of the oil chamber 43 and arranged to have its outer end engage with the 130

walls of the notches 55' on the dial 55, so as to hold the valve stem in any position into which it may be adjusted.

The oil is introduced into the cylinder 41 and normally fills the space between the plunger and the inner end of the cylinder, the duct 41' and the oil chamber 42 when the circuit through the mechanism is closed. When an overload on the circuit occurs the magnet 24^a tends to draw the lower end of the armature inward as heretofore described. The inward movement of the lower end of the armature is opposed by the oil in the retarding device. The inward movement of the plunger 46 tends to force the oil in the chamber 42 into the chamber 43, the adjustment of the conical end 50' of the valve head 50 relative to the walls of the recess 44 tending to check the flow of oil between these two cylinders and to determine the time required for the plunger 46 to move a given distance under a given pressure.

It will be noted that by decreasing the space between the conical walls of the valve head 50 and the walls of the recess 44' a greater period of time will be required for transmitting the oil from the chamber 42 to the chamber 43 and for the incident travel of the plunger 46 in order to force the trigger device 36 back so as to release the switch 1.

When the armature 9 of the mechanism above described is controlled in its operation by means of a retarding device such as the one herein described, it will be seen that it is possible to so regulate the retarding device as to predetermine the time during which the overload may continue on the circuit. The operation of the retarding device at the time an over-load occurs is as follows: The magnet 12 attracts the armature 9, which through the rod 46' exerts an inward pressure on the plunger 46 tending to force the oil as above described from the chamber 42 to the chamber 43. If the over-load continues for a long enough period of time, or for a period greater than that for which the retarding action of the check valve is adjusted, the trigger device 36 will be forced rearward and the rod 29 will be forced downward under the action of the spring 28. But if the over-load does not occur for such a predetermined period of time the circuit through the mechanism will not be broken. When it is desired to close the circuit after it has been opened for any reason, the handle 31 is used, and as before described the rod 29 is raised until the trigger device 36 locks the said rod against downward movement. During this upward movement of the rod 29, the spring 38 acts upon the trigger 36 to force the rod 14 outward. The rod 14 serves by means of the pin 14^a to transmit the force of the spring

38 to the armature 9, and to thus aid in pushing outward the lower end of the armature. As this end of the armature moves outward it draws outward the plunger 46 of the retarding device, this tends to force oil from the chamber 43 through the duct 49^a, unseating the valve 51 in valve head 50 and passing thence into the chamber 42. Oil may also pass from the chamber 43 through the conical space between the valve head 50 and the recess 44' to the chamber 42. It will be seen that in view of the relatively larger passageway, the power necessary to force the oil from the chamber 43 to the chamber 42 is considerably less than that required for the opposite action.

In order to prevent the arcing which occurs between the stationary and movable contacts from seriously injuring the closely adjacent metallic parts of the mechanism, I provide to have this arcing take place in insulated chambers or compartments. These compartments are shown at 56-57. Each is a hollow rectangle comprising the bottom insulating plate 58 and two side walls or plates of insulating material 59-59 and the top plate 60. This rectangle of insulating material is inserted in apertures 61-62 in the side walls 18^b-18^b of the frame and extends inward surrounding both the metal and the carbon contacts within the mechanism. When the switch 1 is thrown down, breaking the circuit, the arcs which occur between the brushes are blown out by the magnetic lines of force passing between the armature 9 and the pole pieces 12^b-12^b arranged in the rear of the casing. This blowing out of the arcs by the lines of force insures an increased life of the brushes and the fact that this arcing occurs entirely within an insulated compartment insures that it will have no detrimental effect upon the metallic parts of the mechanism. The walls of the insulating compartments, as shown, extend outward beyond the side walls 18^b-18^b of the casing to keep the flames from the arcs between the brushes from contacting with said walls.

What I claim is:

1. In a circuit breaker for an electric circuit, the combination of the switch for opening and closing the circuit, means for throwing the switch so as to open the circuit, the anti-friction roller carried by said switch, and a pivoted trigger device having a curved surface concentric with the pivot of the device arranged to engage with said anti-friction roller to hold the circuit closed and means for releasing said trigger device, substantially as set forth.

2. In a circuit breaker for an electric circuit, the combination with the stationary brushes and the movable brushes of means for controlling the operation of the movable brushes, comprising a spring actuated rod

125

130

having anti-friction rollers carried thereby and arranged on opposite sides thereof, and a trigger device adapted to engage with said rollers to hold the said brushes in contact with each other, substantially as set forth.

3. In a circuit breaker for an electric circuit, the combination with the stationary contacts through which the circuit is closed, of a rectilineally movable rod for controlling the movements of the movable contacts, a spring associated with said rod and adapted to exert pressure thereupon, tending to cause it to open the circuit, anti-friction rollers carried by said rod on opposite sides thereof, a trigger device having arms adapted to engage said rollers to hold the circuit through the mechanism closed, means for projecting said trigger arms into the path of travel of the said rollers and means for releasing said trigger device, substantially as set forth.

4. In a circuit breaker for electrical circuits, two contacts, means for holding said contacts in engagement with each other, an electromagnet having a stationary core, an armature arranged to form a pole piece for the magnet at one side of the contacts and arranged to swing away from the said stationary core to open or completely close an air gap between the core and the armature, the said armature being adapted to release said holding means for the contacts, substantially as set forth.

5. In a circuit breaker for an electric circuit, the combination of a switch, means for automatically opening said switch, locking devices attached to said switch, a trigger adapted to engage said locking devices and hold the switch in its closed position, said trigger being adapted to move to permit the movement of the switch from its open to its closed position, an electro-magnet, a movable armature for said magnet, a retarding device connected to said armature and adapted to prevent its rapid movement, and connections between the armature and the trigger whereby movement of the armature toward the magnet will release the trigger, said connections being adapted to permit movement of the trigger independently of the armature, substantially as set forth.

6. In a circuit breaker for an electric circuit, the combination of a switch, means for normally holding the switch in its open position, a locking device on the switch, a trigger adapted to engage the locking device to hold the switch in its closed position, said trigger being adapted to move out of the path of the locking device when the switch is moved from its open to its closed position, an electro-magnet, a movable armature for said electro-magnet, a retarding device connected to said armature and adapted to prevent the rapid movement, connecting means between the arma-

ture and the trigger whereby movement of the armature toward the magnet will release the trigger, said connecting means being adapted to permit movement of the trigger independently of the armature, and a hand-controlled device adapted to engage said connecting means to release the trigger, said hand-controlled device engaging the connecting means independently of the armature, substantially as set forth.

7. In a circuit breaker for an electric circuit, the combination of a switch, automatic means for moving the switch to its open position, a locking device connected to the switch, a trigger adapted to engage the locking device to hold the switch in its closed position, said trigger being adapted to move out of the path of the locking device when the switch is moved from its open to its closed position, a releasing device connected to the trigger, a hand-controlled device adapted to engage the releasing device in such a way as to be capable of moving it only in the direction to release the trigger, an electro-magnet, a movable armature for said magnet, a retarding device connected to the armature and adapted to prevent its rapid movement, said armature engaging said releasing device independently of the engagement of the hand-controlled device in such a way as to be capable of moving it only in the direction to release the trigger, substantially as set forth.

8. In a circuit breaker for an electric circuit, the combination of an electro-magnet having bifurcated core, a stationary switch contact, a movable switch contact, a longitudinally movable rod upon which said movable switch contact is supported, said rod extending between the two prongs of the core, a spring adapted to move the rod to open the switch, a trigger adapted to hold the rod in position with the switch closed, a movable armature mounted adjacent the bifurcated core, and a connection between the armature and the trigger whereby movement of the armature toward the core will release the trigger, substantially as set forth.

9. In a circuit breaker for an electric circuit, the combination of a stationary switch contact, a movable switch contact, a longitudinally movable rod upon which the movable switch contact is supported, means for automatically moving the rod to open the switch, a trigger adapted to engage the rod to hold the switch in closed position, an electro-magnet having a bifurcated core, the two forks of which are located on opposite sides of the said rod, pole pieces on one side of the switch contact and magnetically connected to the core, a movable armature on the side of the switch contacts opposite to the said poles, and a connection between the armature and the trigger whereby movement of the armature toward

70

75

80

85

90

95

100

105

110

115

120

125

130

the core will release the trigger and permit the switch to open, the said poles, core and armature forming a part of a magnetic circuit which passes through the switch contacts and serves to blow out electric arcs between said contacts, substantially as set forth.

In testimony whereof I affix my signature in presence of two witnesses.

FRANK L. SESSIONS.
